UNITED STATES PATENT OFFICE

EISUKE NISHI, OF SUKEGAWA-CHO, JAPAN, ASSIGNOR TO KABUSHIKI-KAISHA
HITACHI-SEISAKUSHO, OF TOKYO, JAPAN, A CORPORATION OF JAPAN

SHOCKPROOF STARTER FOR DIRECT-CURRENT MOTORS

Application filed June 7, 1929, Serial No. 369,171, and in Japan June 20, 1928.

This invention relates to improvements in shock-proof starters for direct current motors.

Hand operated starters for direct current motors, in general, are provided with an electromagnet called the low voltage release, which holds the controlling arm at the zero resistance position when the operating voltage is normal and which releases it allowing it to resume the position of full resistance, when the voltage decreases below a certain pre-determined value.

Owing to the fact that the attraction of the said electromagnet cannot be made sufficiently great from constructional point of view, the starters heretofore employed do not operate satisfactorily, especially when they are exposed to severe shocks and vibrations, such as are met with on men-of-war. In such a case, the electromagnet of a starter is liable to release the controlling arm at the shocks and vibrations resulting from the discharge of a fire-arm, leading to the unwarranted stoppage of the motor.

The present invention aims to obviate the above-mentioned drawbacks. According to the invention, the controlling arm is positively locked and held at its operative position by means of a hook fixed to the controlling arm and engaging with a finger or stopper jointed to a rotatable spindle which is mounted upon the panel of the starter. The stopper or finger is turnable in a vertical plane around a horizontal pin mounted on the spindle. The said spindle, being connected with an armature of an electromagnet forming the low voltage release, will support the stopper at a certain position to firmly take hold of the controlling arm, as long as the electromagnet is energized, while, when the electromagnet is de-energized, the spindle will be allowed to rotate on its own axis, and conjointly therewith the stopper rotates and its sense of yieldability will be brought to coincide with the direction of motion of the hook attached to

the controlling arm, thereby the latter will be released; under the action of a return spring, to resume the position of full resistance.

For a better understanding of my invention, reference may now be had to the accompanying drawings forming a part of this specification, in which like characters of reference designate like parts throughout the several views.

Figure 1 is a plan view of a starter according to the invention;

Figure 2 is a fragmentary plan view, on an enlarged scale, showing the controlling arm as held at the operative position by the stopper associated with the low voltage release;

Figure 3 is an end elevation view of the parts shown in Figure 2;

Figure 4 is a fragmentary elevational view showing entire locking device at its operative position.

Figure 5 is a plan view of a modified form of a starter according to the invention;

Figure 6 is a fragmentary cross-sectional view, the section being taken substantially on line VI—VI of Figure 5.

In the drawings, A is the controlling arm pivotally mounted at one of its ends on a stationary axis 1 and provided at the other with a hook 2. Mounted on the back side of the controlling arm is a contact bridge 3. 4 is the handle for manipulating the arm. f are contact pieces so disposed as to lie along the periphery of a circle drawn the stationary axis 1 as centre and connected to successive taps attached to the starting resistance. c is a conductive plate connected to one terminal of the main circuit. The contact bridge 3 makes a sliding contact with the plate c to electrically connect the plate with one or adjoining two of the contact pieces f. The above mentioned construction does not materially differ from the corresponding parts of any ordinary starter.

5 is a rotatable spindle supported by the bearings 6 and 7 which are provided near the last one of the series of contact pieces. 8 is a finger or stopper mounted at the outer end of the spindle 5, being turnable around a horizontal pin 9. Fixed to the rotatable spindle 5, as by a screw 7, is an iron armature 10 to be attracted to the pole pieces P of the electromagnet 11 when the same is energized. 12 are distance pieces. Disposed around the spindle 5 is a spiral spring 12 fixed at one of its ends to one of the bearings 7 and at the other to the iron armature 10 and tending to bring the armature 10, together with the spindle and the stopper 8, away from the pole pieces P of the electromagnet 11. Adjacent to the spindle 5, preferably underneath thereof, is an auxiliary spindle 14 provided with a spiral spring 13. This spring 13 is fixed at one of its ends on the bearing 7 and bears at the other end on a bent arm 15 provided on the spindle 14, the free end of the bent arm in turn bears against the downwardly extending portion a of the iron piece 10. The action of the spring 13 is to turn the spindle 5 in the opposite direction to that of the spring 12. The springs 12, 13 and their leverages of action are so proportioned that normally the action of the latter one 13 overbalances that of the former 12, and the iron armature 10 is forced to contact with the pole pieces P of the electromagnet, the horizontal pin 9 assuming the position parallel to the panel board, as shown in the various figures. 16 is a push plate fixed to the controlling arm A. When the controlling arm is moved from the position of the maximum resistance to that of the least resistance, the push plate will come to contact with the bent arm 15 attached to the auxiliary spindle 14 and will displace the bent arm away from the engagement with the depending portion a of the iron armature 10. In this manner, while the controlling arm is held in its operative position, the iron armature 10 and the parts associated with it, will be isolated from the action of the auxiliary counter-acting spring 13, ready to coil back due to the sole resilient action of the main spring 12, as soon as the attractive force of the electromagnet 11 sinks below a certain predetermined value. 17 is a tension spring normally holding the stopper 8 substantially at an upright position.

When the controlling arm A is finally brought to its operative position shown in Figures 2 and 3, the stopper 8 will be pushed forwardly, against the action of the tension spring 17, by the inclined surface at the top end of the hook 2 and engages therewith, and the controlling arm will be positively locked at the operative position.

When the electric motor, for which the device according to the present invention is equipped with, is desired to be started, the controlling arm A is gradually moved to the

right from its extreme left position (Fig. 1). During this initial period of starting, the attractive force of the electromagnet is necessarily not great. However owing to the fact that the action of the more powerful spring 12 overbalances that of the recoil spring 12, the spindle 5 will be firmly held at its locking position, in which, the rocking axis 9 of the stopper 8 is in the direction tangent to the circle of travel of the hook 2, that is, the plane of yieldability of the stopper 8 will be perpendicular to the travel of the hook 2.

When the controlling arm is brought close to the final operative position, the stopper 8 will be pushed forwardly by the inclined surface at the extreme end of the hook 2 and finally is engaged with the hook, positively locking the controlling arm at the operating position (Figs. 2 and 3). Simultaneously with the locking action just mentioned, the bent arm 15 of the auxiliary spindle 14 will be displaced away from its contact with the extended portion a of the iron armature 10, as indicated by dotted lines in Figure 3, and in this manner, the entire locking device comprising the spindle 5, stopper 8 and the iron armature 10 will be freed from the action of the auxiliary spring 13, making ready for the locking device to turn around the spindle 5 under the action of the recoil spring 12 as soon as the attractive force of the electromagnet decreases down to a certain predetermined value.

In this locking position, the plane with which the stopper 8 is capable to turn around the pin 9, or the sense of yieldability of the stopper, is in a direction perpendicular to the travel of the hook 2. Consequently, the controlling arm cannot be disengaged from the locking device, until the sense of yieldability of the stopper coincides with the direction of travel of the hook due to the rotation of the spindle 5 resulting from the releasing by the electromagnet 11 of the iron armature 10.

When the attractive force of the electromagnet decreases owing to the lowering or disappearance of the supplied voltage, the spindle 5 will be rotated by a right angle in clockwise direction (Figure 3) under the recoil action of the spring 12 and the sense of yieldability will be brought to coincide with the direction of travel of the hook, and consequently the controlling arm A will be brought back to the initial position of full resistance under the action of the return spring 8. In this case, the bent arm 15, being freed from the action of the push plate 16, recoils back under the action of the spring 12 and again acts upon the iron armature 10 at its extending portion a and holds the stopper 8, against the action of the weaker spring 12, at its normal position shown in the figures to be ready for another engagement with the hook 2.

As above explained, according to the inven-

tion, the stopper is initially held in such a manner that the sense of yieldability is perpendicular to the travel of the hook. The hook, therefore, is firmly held in its operative position, being in positive engagement with the stopper, to be released only by the rotation of the plane of yieldability consequent to the rotation of the main spindle as caused by the releasing of iron armature by the electromagnet. Since the plane of yieldability of the stopper remains perpendicular to the travel of the hook attached to the controlling arm as long as the electromagnet is energized, there is no possibility that the controlling arm is released by shocks and vibrations during the operation of the motor.

It has been stated in the above that the plane of yieldability rotates by a right angle when the armature is released by the electromagnet. However, this angle may be an angle greater or less than the right angle.

In the modification shown in Figures 5 and 6, the auxiliary spindle 14 is dispensed with and the auxiliary spring 13, which counteracts and overbalances the action of the main spring 12, is mounted on the same spindle 5 as the main spring. In this construction, a disc-like piece 18 formed with a projecting

30 nose 19 is rotatably mounted on the spindle 5 and is connected to one end of the spring 13. The disc 18 is further provided with a projection 20 extending parallel to the spindle and adapted to act on the extended portion *a* of the armature 10 when the disc is not acted upon by the push plate 16 of the controlling arm. The other parts of the construction and the function of the device are similar to those of the device shown in Figures 1 to 4.

40 It will be apparent to those skilled in the art that the invention is not limited to the modifications which have been actually illustrated, but, on the contrary, various minor changes and modifications may be made without departing from the spirit of my invention or from the scope of the appended claims.

What I claim is:—

1. Shock proof starter, comprising a controlling arm, a hook fixed to the said controlling arm, a rotatable spindle, an electromagnetic means adapted to act on the said spindle, a stopper jointed to the said spindle in such a manner that it is yieldable in one sense only and adapted to come into a positive engagement with the said hook as long as the said electro-magnetic means is energized, the said stopper releasing the said hook freely when the said spindle rotates owing to the releasing action of the said electro-magnetic means.

2. Shock proof starter, comprising a controlling arm, an electromagnet, a hook fixed to the said controlling arm, a spindle, an iron piece associated with the said spindle

and co-operating with the said electromagnet, and a stopper provided on the said spindle to come into a positive engagement with the said hook as long as the said iron piece is attracted by the electromagnet, the said stopper releasing the said hook freely when the said spindle rotates owing to the release of the iron piece by the electromagnet.

3. Shock proof starter, comprising a controlling arm, an electromagnet, a hook fixed to the said controlling arm, a spindle, an iron piece fixed to the said spindle and co-operating with the said electromagnet, and a stopper adapted to be engaged with the said hook and jointed to the said spindle in such a manner that normally it maintains a substantially upright position and is turnable in one sense only.

4. Shock proof starter, comprising a controlling arm, an electromagnet, a hook fixed to the said controlling arm, a spindle adjacent to the said electromagnet, an iron piece mounted on the said spindle and co-operating with the said electromagnet, and a stopper adapted to be engaged with the said hook and jointed to the said spindle in such a manner that the sense of its yieldability coincides with the direction of motion of the hook when the spindle is rotated upon the releasing of the said iron piece by the electromagnet.

5. Shock proof starter, comprising a controlling arm, an electromagnet, a hook fixed to the said controlling arm, a spindle adjacent to the said electromagnet, an iron piece mounted on the said spindle and co-operating with the said electromagnet, a recoil spring provided around the said spindle, an auxiliary spindle adjacent to the said first mentioned main spindle, a coiled spring provided around the auxiliary spindle strong enough to normally hold the said iron piece on to the poles of the electromagnet against the action of the said recoil spring, and a stopper adapted to be engaged with the said hook and jointed to the said spindle in such a manner that the sense of its yieldability coincides with the direction of motion of the hook when the spindle is rotated upon the releasing of the said iron piece by the electromagnet.

6. Shock proof starter, comprising a controlling arm, an electromagnet, a hook fixed to the said controlling arm, a spindle adjacent to the said electromagnet, an iron piece mounted on the said spindle and co-operating with the said electromagnet, a recoil spring provided around the said spindle, an auxiliary spindle adjacent to the said first mentioned main spindle, a coiled spring provided around the auxiliary spindle strong enough to normally hold the said iron piece on to the poles of the electromagnet against the action of the said recoil spring, a stopper adapted to be engaged with the said hook and

jointed to the said spindle in such a manner that the sense of its yieldability coincides with the direction of motion of the hook when the main spindle is rotated upon the releasing of the said iron piece by the electromagnet, and means provided on the controlling arm to hold the auxiliary coiled spring in its inoperative position as long as the controlling arm is in the operative locked position.

10 In testimony whereof I affix my signature.
